(57) **CLAIM**

We claim the ornamental design for an oil filter, as shown and described.

DESCRIPTION

FIG. 1 is a front perspective view from above of an oil filter, according to the claimed design;

FIG. 2 is a front perspective view from below of the claimed design of FIG. 1;

FIG. 3 is a front view of the claimed design of FIG. 1;

FIG. 4 is a rear view of the claimed design of FIG. 1;

FIG. 5 is a right side view of the claimed design of FIG. 1;

FIG. 6 is a left side view of the claimed design of FIG. 1;

FIG. 7 is a top view of the claimed design of FIG. 1; and,

FIG. 8 is a bottom view of the claimed design of FIG. 1.

One exemplary use of an oil filter embodying one or more of the ornamental designs shown or described herein is as an oil filter for use in a small internal combustion engine.

Any portion of the article depicted in broken lines forms no part of the claimed design.

1 Claim, 7 Drawing Sheets
